UNITED STATES PATENT OFFICE.

ROBERT STEWART, OF NEW YORK, N. Y.

DISPENSING APPLICATOR.

Application filed May 27, 1927. Serial No. 194,780.

The present invention relates to a dispensing applicator of the general character disclosed in my prior Patent No. 1,646,324 of October 18, 1927. In accordance with the 5 present invention the construction of the device has been materially simplified and the cost of manufacture greatly reduced. This has been accomplished in the first place by using a conventional bottle for a container, and in the second place by using a cork and cover to cooperatively define an outlet and closure instead of defining a stop outlet in the container proper.

Objects of the invention are to provide 15 a dispensing applicator primarily designed for use in connection with containers of hair tonic or the like which is equipped with means for controlling the discharge of its liquid contents, and with means for applying the discharge contents, preferably in 20 the nature of a cap having a series of massaging tits thereon.

Other objects of the invention are to provide 25 a dispensing applicator which will insure an effective seal against evaporation or accidental spilling of the contents of the container when the device is not in use.

Still further objects are to provide a device of this character which may be conveniently manually manipulated to control the 30 outlet and which will combine simplicity of construction with ruggedness and durability in use.

With the above noted and other objects 35 in view, the invention consists in certain novel features of construction and combinations and arrangements of parts, as will be more fully hereinafter set forth and pointed out in the claims. The invention may be 40 more fully understood from the following description in connection with the accompanying drawings, wherein—

Fig. 1 is a view in side elevation of a device embodying the invention.

Fig. 2 is a top plan view thereof.

Fig. 3 is a vertical sectional detail on the line 3—3 of Fig. 2.

Fig. 4 is a view partly in section and partly in elevation, showing the manner in 50 which the outlet opening is sealed by rotating the cap.

In the drawings I have used the numeral 10 to designate an ordinary bottle provided with a neck 11, and an outwardly projecting flange or lip 12. This bottle or other container carries the liquid to be dispensed, and

fitted into the bottle neck is a closure 13 preferably of rubber, having an outlet passageway 14 extending therethrough. The body of the cork lies substantially flush with the mouth of the bottle, but the material around the outlet passageway defines a flexible rubber neck 14^a projecting above the outer surface of the cork and adapted for disposition in an opening 15 formed in a rubber cap 16. The latter includes depending flange portions 17 embracing the bottle neck, and if desired grooved at 18 for the reception of the lip 12. To facilitate rotation of the cap 17, the latter may be provided with ribs or other convenient hand grips 19.

The outlet passage 14 and the opening 15 are eccentrically disposed relatively to the axis of the bottle, so that rotation of the cap serves either to expose the outlet opening 14, or to crush and fold the nipple 14^a over, as seen in Fig. 4.

The nipple 14^a being of relatively thin rubber immediately springs to the position of Fig. 3 when aligned with the opening 15, and may be readily distorted and folded over as seen in Fig. 4 when the cap has been rotated to move the opening 15 out of alignment with the passage 14. By virtue of this construction a very effective seal is obtained.

Preferably, a number of massaging tits or equivalent devices 20 project from the face of the cap 16, and may be used for rubbing the hair tonic or other material from the bottle into the hair after the material has been dispensed by shaking the bottle.

It is to be understood that while I have referred to the container as a bottle, it may be in the nature of a can or other device, and the closure and cap are not necessarily of rubber. The cap for instance, might be of metal construction, and the plug 13 might be of cork.

In fact various changes and alterations 100 might be made in the general form and arrangement of the parts described without departing from the invention. Hence I do not wish to limit myself to the details set forth, but shall consider myself at liberty to 105 make such changes and alterations as fairly fall within the spirit and scope of the appended claims.

I claim:

1. In combination, a container, a plug fitting within the mouth of the container and having an outlet passage therein, a closure

cap rotatably mounted on the container and covering the plug, and having an opening therein adapted to be selectively aligned with the passage in the plug by rotating the cap, the cap and plug including means acting to mechanically seal the passage when the cap is in passage-closing position, said means comprising a hollow flexible nipple on the plug encircling the outer end of the passage and folded over by the cap.

2. In combination, a container, a plug fitting within the mouth of the container and having an outlet passage therein, a closure cap rotatably mounted on the container and covering the plug, and having an opening

therein adapted to be selectively aligned with the passage in the plug by rotating the cap, the cap and plug including means acting to mechanically seal the passage when the cap is in passage-closing position, said means comprising a hollow flexible nipple on the plug encircling the outer end of the passage and folded over by the cap, said cap being of distortable resilient material pressed outwardly by the folded nipple. 20

3. A device as described in claim 1, wherein the plug and nipple are of rubber and integral with each other. 25

ROBERT STEWART.
